CLAIM

The ornamental design for a pacifier cap as shown and described.

DESCRIPTION

FIG. 1 is a front, right perspective view of a pacifier cap showing our new design.

FIG. 2 is a rear, left perspective view thereof.

FIG. 3 is a right view thereof.

FIG. 4 is a left view thereof.

FIG. 5 is a top view thereof.

FIG. 6 is a front view thereof.

FIG. 7 is a bottom view thereof.

FIG. 8 is a rear view thereof.

FIG. 9 is a front, right perspective view of the pacifier cap in an assembled position with a pacifier.

FIG. 10 is a rear, left perspective view thereof.

FIG. 11 is a right view thereof.

FIG. 12 is a right view thereof.

FIG. 13 is a top view thereof.

FIG. 14 is a front view thereof.

FIG. 15 is a bottom view thereof; and,

FIG. 16 is a rear view thereof.

The broken lines of equal length represent unclaimed subject matter and form no part of the claimed design.

1 Claim, 8 Drawing Sheets
